UNITED STATES PATENT OFFICE.

WILLIAM PEET, OF KANSAS CITY, MISSOURI.

BOX-END-SEALING MACHINE.

1,349,432.

Specification of Letters Patent. Patented Aug. 10, 1920.

Application filed June 18, 1919. Serial No. 305,082.

To all whom it may concern:

Be it known that I, WILLIAM PEET, a citizen of the United States, and resident of Kansas City, county of Jackson, and State 5 of Missouri, have invented a new and useful Box-End-Sealing Machine, of which the following is a specification.

This invention relates to improvements in machines for sealing the closure flaps of 10 boxes or cartons such as paper boxes and has for one of its objects the provision of a machine of this character which will be compact, inexpensive in construction and operation, and capable of rapidly and effectively sealing boxes.

Another object of the invention is to provide a machine of the character described which provides for the setting of the adhesive used to seal the closure flaps, there 20 being provided means for applying pressure to the flaps and holding them under pressure so as to facilitate such setting and insure a tight and reliable sealing of the flaps.

Another object of the invention is to provide a novel means for controlling the operation of the machine so that the speed of the machine and rapidity with which the boxes are sealed may be varied at will by 30 the operator, the feeding of the boxes and the folding of the flaps thereof being done by the operator.

The invention possesses other advantageous features, some of which, with the foregoing, will be set forth at length in the following description, where I shall outline in full, that form of the invention which I have selected for illustration in the drawings accompanying and forming part of 40 the present specification. In said drawings I have shown one form of the device of my invention, but it is to be understood that I do not limit myself to such form, since the invention, as expressed in the claims may 50 be embodied in a plurality of other forms.

Referring to the drawings:

Figure 1 is a top plan view of a machine constructed in accordance with this invention, being broken away in part for the sake 60 of clearness of illustration.

Fig. 2 is a vertical sectional view taken on line 2—2 of Fig. 1.

Fig. 3 is a detail view of the means for

controlling the speed of operation of the machine, shown in side elevation and in section.

Fig. 4 is a top plan view of a modified form of the invention, and

Fig. 5 is a vertical sectional view of the frame of the modified form of invention 60 shown in Fig. 4.

The machine of this invention principally comprises a rotary frame carrying members for supporting boxes to be sealed and means for applying pressure to the 65 folded bottom closure flaps of the boxes so as to cause the adhesive to set and insure a reliable and in fact a permanent sealing of such flaps. There is also provided means for varying the speed of rotation of the frame 70 which is in the form of a clutch and acts to intermittently transmit rotatory movement to the frame so that the supporting members advance one at a time past a point at which the operator stands. As each supporting member is presented to the operator he places a box thereon, applies adhesive material to the flaps, folds the flaps into position and operates the pressure applying means so as to apply pressure to the 80 thus folded flaps. The box thus sealed is carried around with the frame and when again opposite the operator the adhesive has had time to set and the flaps will remain securely sealed.

In the construction of the machine there is provided a frame 6 which is preferably circular and rotatably supported on a circular track 7, by rollers 8, said rollers being secured to the lower side of the frame by 90 brackets 9. The frame comprises two annular plates 10 and 11 arranged one above the other in parallel relation and joined by vertical posts or rods 12. Brace bars 12' are secured to the rods 12 between the plates 95 10 and 11. Carried upon the frame 6 is the means for supporting boxes to be sealed and said means consists of a plurality of supporting members 13 which are pivotally mounted upon the plate 11 of the frame and 100 arranged to swing outwardly away from the periphery of the frame in order that boxes may be placed thereon and removed therefrom. Each member 13 preferably comprises a pair of vertical spaced and parallel 105 rods 14 which are hinged at 15 to the plate

11 of the frame. Mounted upon these rods are supporting plates 16 and 17 arranged one above the other. The plate 16 is substantially equal in size to the inside area of the boxes and the flaps of the boxes are folded upon said plate. The plate 17 is longer than the boxes are wide and the lower edges of the boxes rest on this plate as shown in Fig. 2. These plates are so spaced apart that when the edges of the box rest on the plate 17 the flaps on the upper side of the box may be folded in and will be supported by the plate 16 which plate lies within the box. The plates 17 have apertured bosses therein 18 through which the rods 14 extend and set screws 19 hold the plates in position upon said rods. Thus the plates 17 are adjustable and provide for the operation of the machine with boxes of various sizes. The plates 16 are removably secured to the rods 14 by set screws 20 so as to permit of the use of different sized plates in accordance with the size of the boxes to be sealed by the machine.

There are provided stop members 21 which are secured to the rods 12 and embrace the rods 14. These stop members extend outwardly and downwardly from the rods 12 and are engaged by the rods 14 when the rods are swung out as shown in Fig. 2, so as to limit the outward movement of said rods.

Means is provided for holding the boxes upright on the supporting members 13 and for guiding and centering the boxes relative to said supports. This means comprises resilient substantially U shaped spring metal bars 22 which are removably secured intermediate to their ends as at 23 to the brace bars 12' as shown in Fig. 1 and have their portions 24 parallel except at their free ends which ends diverge outwardly. These arms are spaced apart so as to engage and clamp the sides of a box to be sealed and when the members 13 are moved into vertical position the boxes thereon will extend and be held between and by the arms 24 of said members 22.

The means for applying pressure to the folded flaps and for sealing the boxes is mounted upon the plate 10 of the frame and comprises a plurality of independent pressure or sealing devices 25 spaced apart to correspond to the spacing of the members 13. Each of the devices 25 comprises a flat pressure or sealing plate 26 supported by a rod 27. The rod 27 is vertically slidably mounted in the plate 10 and extends above said plate into and through a cylindrical casing or housing 28. This casing is mounted in a supporting plate 29 therefor and which is secured to the plate 10. Mounted in the casing 28 is an expansion helical spring 30. The upper end of this spring is engaged by a cross piece or head 31 which head, is secured to the upper end

of the rod 27, holds the spring in place and operates in opposed slots 32 formed in the said casing 28. The spring tends to urge the rod 27 and plate 26 upwardly out of the path of the boxes and supporting members 13.

Mounted for rotating or turning movement in the casing 28 is a cam operating member 33 having a handle 34. Stops 35 and 36 are provided on said member at the extremities of the cam surfaces thereof so as to limit the movement of the cam in both directions. The cam rides upon the upper end of the rod 27 and the pin 37 on which the cam turns is located off center so that when the handle is moved into up or vertical position the cam allows the spring 30 to urge the rod 27 and plate 26 upwardly and out of operative position whereas when the handle is moved into horizontal position the cam forces the rod and plate downwardly into operative position against the action of the spring 30. There may be provided a guide rod 38 secured to the plate 26 and extending upwardly through an opening 39 in the plate 10. When the plates 16 and 26 are in the position shown in Fig. 2 the flaps are pressed between the plates and the sealing of the flaps is effected.

Mounted upon the supporting surface 40 which supports the track 7 is a motor 41 having a drive shaft 41' which carries a worm 43. A worm wheel 44 is mounted on the support 40 and is driven by said worm 43. Rotatably mounted as at 45 at one end, 10 centrally of the track 7 or the support 40 is an arm 46 the other end of which is disposed so as to lie close to the plate 11. A slot 47 is formed in this arm and receives a block 48 slidably mounted therein and which 10 is secured to the worm wheel 44. When the wheel turns, the block and slot arrangement cause the arm to oscillate.

The arm is provided with means for connecting the frame 6 therewith so as to transmit rotary motion to said frame and this means comprises a pawl or dog 49 which is pivoted to the arm 46 near the free end of said arm. The end 50 of this pawl 49 is arranged to engage in spaced notches 51 formed on the inner periphery of the plate 11 of the frame 6. A spring 52 is attached to the arm 46 and pawl 49 and tends to force the pawl into the notches.

The elements described in the foregoing 12 constitute the means for operatively connecting the motor with the frame so as to produce intermittent rotation or movement of said frame, and there is provided means for throwing this connecting means out of operation and for holding such means in inoperative position. This latter means constitutes a trip member 53 which is pivoted as at 54 upon the support 40 and is arranged to engage the pawl 49 so as to move said 13

5 pawl out of engagement with the notches 51. A pedal 55 is pivotally mounted as at 56 on the support 40 and a link or bar 57 connects the pedal with the trip. This pedal when depressed pulls on the bar 57 which moves the trip 53 so that the pawl 49 is engaged and moved out of the notch 51.

10 In the operation of the machine the operator stands near the pedal 55 and when the motor is running the arm 46 is oscillated from right to left so that the pawl 49 will engage in one of the notches 51 and move the frame a distance equal to the degree of movement of the arm in one direction. The 15 notches are so arranged that each time the arm 46 is moved to the left the frame is likewise moved or rotated. Thus the members 13 are intermittently brought opposite the operator and at the beginning of the operation 20 of the machine the operator places a box such as the one 58 upon the adjacent member 13 so that the box passes over the plates 16 and the lower edges of the box rest upon the plates 17. The flaps of the upper 25 side of the box are extended above the plate 16 and the operator applies adhesive material thereto and then folds the flaps, one upon the other in the ordinary manner. The members 13 lie in their outwardly inclined positions, as shown in Figs. 1 and 2, 30 when empty, and are thus accessible to the operator. After the flaps are folded the members 13 and the box are pushed into position to seal the flaps and the bars 22 35 embrace the side of the box and hold it in position. The handle 34 of the member 33 is pulled down by the operator causing the plate 26 with the plate 16 to press and seal the flaps. The operations of putting the 40 box on the support, pushing the support and box in place and moving the pressure plate into position are done between movements of the frame, sufficient time being provided, by the spacing of the notches 51, to permit 45 of these operations.

After operating the pressure device 25 the box thus operated upon is carried around with the frame and when again presented opposite the operator is removed, it having 50 been held in the machine under pressure sufficiently long to insure the setting of the adhesive and provide for a reliable sealing of the flaps.

To remove the box the operator pushes 55 upwardly on the handle 34 of the cam 33 and this allows the spring 30 to force the rod 27 and plate 26 upwardly, the latter away from the flaps. The member 13 is then pulled outwardly to its inclined position and the box may be readily removed 60 so that a new unsealed box may be placed on said member 13. The operator has sufficient time to remove the box and place an unsealed box in position before the next 65 advancement of the frame is effected.

The operator may, if it becomes necessary to prevent motion or advancement of the frame, press upon the pedal 55 and cause the trip 53 to engage and move the pawl 49 into such position that it will not engage in 70 the notch 51 with which it is timed to engage, or if engaged in one of the notches the trip will move the pawl out of such engagement and stop operation of the frame. The arm 46 will oscillate freely and not 75 transmit motion to the frame when the pawl 49 is thus held. The spring 52 will serve to move the pawl back into operative position when the pedal 53 is released and the movement of the frame will continue. In 80 this manner it will be seen that the operator may, as each of the members 13 is presented, place boxes upon such members and seal the flaps. After the boxes are sealed and again 85 presented to the operator, having been carried around with the frame, the operator effects the removal of the boxes thus sealed and the positioning of new boxes to be sealed by the machine, this cycle of operation being continuous. 90

Rapidity of operation is facilitated by having the stops 35 and 36 on the cam 33 and by providing the stop members 21. The stops 35 permit of the handle 34 being grasped and quickly moved into either position and this is true of the members 13 95 with relation to the stops 21.

This machine while especially designed for sealing the bottom flaps of paper boxes or cartons may be otherwise used as will be 100 obvious. However the sealing provided by this machine is of a somewhat permanent nature since the bottom flaps of such boxes seldom need be opened or unsealed. By provision of adjustability of the various 105 elements of the machine boxes of various sizes and shapes may be operated upon or sealed.

Referring particularly to Figs. 4 and 5 wherein there is illustrated a modified form 110 of the invention there is provided a frame 60 which comprises upper and lower frame members 61 and 62 each comprising a pair of annular angle iron rings 63. These rings are joined by spaced plates 64 and certain 115 of the plates on the lower frame members are notched as at 65 so as to coöperate with the operating means not shown in this form of the invention. These frame members 61 and 62 are joined by crossed brace bars 66 120 and by vertical bars 67. In all other respects this form will correspond to the preferred form, the modification residing in the frame of the machine alone.

I claim:

1. A machine for sealing the flaps of boxes comprising a frame, members for supporting boxes to be sealed carried upon the frame, means for moving said frame to present the supporting members one at a time 130

to a point at which an operator is stationed, pressure devices for applying pressure to and sealing the flaps, said supporting members being mounted to swing outwardly 5 away from the frame, in receiving boxes and upon the removal of boxes therefrom, and means to engage the boxes and releas- 10 ingly hold them and the supporting members in upright position during the sealing operation.

2. In a device of the character described a frame, a plurality of box supporting members, arranged on said frame, a plurality of pressure applying devices for sealing the 15 flaps of boxes mounted on the frame over the supporting members, means to rotate the frame, said supporting members being mounted to swing outwardly away from the frame and means independent of the sup- 20 porting members and pressure devices for engaging the boxes and holding them and the supporting members in position when the supporting members are swung in to- 25 ward the frame.

3. In a machine of the character described, a frame, a plurality of box supporting members on the frame, a plurality of pressure applying devices coöperating with the sup- 30 porting members, a motor, means for connecting the frame with the motor so as to intermittently rotate the frame and means

for throwing said last named means into or out of operation.

4. In a machine of the character described, a frame, a plurality of box supporting members on said frame, each of said members comprised of a box flap supporting plate upon which box flaps are folded, a box supporting plate upon which the lower portions of a box rest, a rod for supporting said 40 plates one above the other, and spring metal members adapted to embrace and hold boxes which are supported by said supporting members.

5. A machine for sealing the flaps of 45 boxes comprising a frame, devices for applying pressure to and sealing the flaps, members for supporting boxes to be sealed carried by said frame and mounted to swing from out of alinement with said devices, and 50 means independent of said supporting members and pressure devices adapted to engage and hold a box in position when one of said members are alined with a coöperating pressure device.

In testimony whereof I have hereunto set my hand at Kansas City, Kansas, this ninth day of June, 1919.

WILLIAM PEET.

In presence of—

C. R. RATHBONE,
W. F. ALBRECHT.
